US00D416545S

United States Patent [19]

Nicklos et al.

[11] Patent Number: Des. 416,545

[45] Date of Patent: ** *Nov. 16, 1999

[54] COMPUTER DATA STORAGE DEVICE

[75] Inventors: **Carl F. Nicklos**, Ogden, Utah; **Nicholas Brawne**, Columbus, Ohio[73] Assignee: **Iomega Corporation**, Roy, Utah

[*] Notice: This patent is subject to a terminal disclaimer.

[**] Term: **14 Years**[21] Appl. No.: **29/049,704**[22] Filed: **Jan. 29, 1996****Related U.S. Application Data**

[63] Continuation of application No. 29/048,747, Aug. 25, 1995, Pat. No. Des. 377,644.

CLAIM

The ornamental design for a computer data storage device, as shown and described.

DESCRIPTION

FIG. 1 is a top front and side perspective view of a computer data storage device incorporating our new design; FIG. 2 is a bottom front and side perspective view thereof; FIG. 3 is a rear elevational view thereof; FIG. 4 is a top plan view thereof; FIG. 5 is a bottom plan view thereof; FIG. 6 is a side elevational view thereof; and FIG. 7 is an opposite side elevational view thereof; and, FIG. 8 is a front elevational view thereof. The broken lines shown in the views are for illustrative purposes only and form no part of the claimed design.
